UNITED STATES PATENT OFFICE.

VICTOR A. VILLAR, OF NEW YORK, N. Y., AND STAFFORD C. TALBOT, OF LONDON, ENGLAND.

LAND-TORPEDO.

1,211,015.

Specification of Letters Patent. Patented Jan. 2, 1917.

Application filed November 13, 1915. Serial No. 61,307.

To all whom it may concern:

Be it known that we, VICTOR A. VILLAR, a citizen of the United States, and residing at New York, in the county and State of New York, and STAFFORD C. TALBOT, a subject of the King of Great Britain, and residing at London, England, have invented certain new and useful Improvements in Land-Torpedoes, of which the following is a specification.

This invention relates to implements of war, and the object thereof is to provide means which may be used either in an offensive or in a defensive manner but which are primarily designed for preparing a way along an impeded front for a charge by an offensive force upon an entrenched force, and which preparation is accomplished without casualties to the former.

In modern warfare one of the main factors of defense consists of entanglements arranged in the path of an attacking force to prevent a charge in force and to delay or prevent progress.

It is the present practice to manually hack a way through these entanglements, with the consequent loss of life or limb, or else to bombard the entanglements from a distance, the latter being slow, costly, and highly unsatisfactory in view of the fact that such entanglements are usually formed of barbed wire arranged along a considerable front, either strung along posts or strewn over the ground in a twisted or snarled state, and artillery projectiles pass therethrough without being exploded.

This device contemplates the transportation of an explosive charge directly to the desired point of damage to the obstructions by automatic means and exploding the charge only when properly located, thus causing a breach or gap of a width and depth determined by the force of the explosion and through which gap the attacking force may charge. By simultaneously employing a plurality of these war implements, suitably spaced apart, substantially an entire front of entanglements or obstructions may be demolished, and without the loss of a man.

It is further contemplated to provide means at a safe distance for exploding the charge, for controlling the motor, and for the recovery of the implement if, for any reason, such recovery is desired, and also to

construct the implement of such materials and in such a manner as to not entail a material financial loss in the destruction of the implement when the explosive charge carried thereby is fired.

The invention is fully described in the following specification, of which the accompanying drawings form a part, in which like characters refer to like parts in each of the views, and in which:

Figure 1 is a side view of the invention in exploding position, showing the entanglements which it is desired to destroy, and showing the control and recovery means for the invention; Fig. 2 is an enlarged longitudinal central section taken through the invention; and Fig. 3 is a plan view of the invention, partly in section.

In the drawings forming a part of this application is shown a simple embodiment of the invention, comprising a vehicle 4 carrying a motor 5 connected with a suitable source of energy 6, an explosive container 7, a firing line 8, a control and recovery cable 9, means 10 operatively connecting the motor with the vehicle wheels, and a shield 11 for the motor elements to protect the same against rifle fire.

The vehicle 4 consists of a frame 4^a having axles 4^b and 4^c carrying wheels 4^d fixed thereto, said axles being rotatably mounted in the frame and provided, each, with sprocket wheels 4^e at the ends thereof and the respective sprockets are joined by sprocket-chains 4^f, all of the wheels being thus actuated simultaneously and similarly. This duplicate arrangement of sprocket-chains is provided to guard against disabling of the device in the event of one of said chains being damaged by a rifle ball.

The motor 5 is shown as of two-cylinder, horizontal, steam engine type, the connecting rods of which are operatively joined to a shaft 5^a carrying a spur-pinion 5^b enmeshed with a spur-gear 5^c upon the rear axle 4^c. The cylinders of the engine are connected with the boiler 6 by means of a supply pipe 5^d having a control valve 5^e therein provided with a handle 5^f, and it will thus be seen that the speed of the engine may be controlled and thus place the speed of the vehicle under control. No engine reverse is contemplated at this time, as it is desired to manufacture the device in as simple and economical a form as possible, but such

mechanism could be provided if desired according to the contemplated use of the implement.

The boiler 6 may be of any desired type and be provided with a fire-box and stack, not shown, or a tank for compressed air might be substituted for the steam boiler, these features being determined according to the contemplated use of the implement, and the estimated range of action thereof, or a storage battery might be substituted for the boiler and an electric motor be substituted for the engine shown, the intent being to provide a simple and inexpensive automobile for transporting the charge in the container 7 to the point of use.

The container 7 will be made of sufficient strength to withstand rifle fire, as there is little likelihood that the enemy could train artillery on the device in the brief period during which it is exposed and at the high speed at which it is designed to drive it, but the shield 11 is provided for the relatively delicate motor elements.

The firing line 8 may be of the electric type now used in blasting rock, or it may be of lanyard type and used with a primer as in some forms of artillery, there being no desire to limit the invention to any specific type.

The control cable 9 is shown as connected with the valve handle 5^a whereby the said valve may be controlled from the rear, as from the trench 12, in the forward movement of the device toward the entanglements 13, Fig. 1, and said cable is also connected at 9^a with a fixed part of the frame 4^a and the rear end thereof may be wound upon a windlass 14 provided with a foot-brake 15.

In practice, the device is prepared for action in a sheltered place, as in the trench 12, and then run up to ground level, and aimed at the entanglements 13, after which the valve 5^a may be set at desired engine speed and the device moves forwardly.

Traction is assured because of the spiked wheels 4^a and the line 8 and cable 9 are paid out as required, although the speed of the device may be controlled by means of the cable and foot-brake 15. If it is found that the device cannot reach the target, because of surface conditions over which it is moving, the cable may be used to close the valve 5^a and to draw the device back to the trench 12, for aiming in a new direction. 55

When the device has reached the entanglements 13 the charge in the container 7 is fired through the medium of the line 8, and great destruction of the entanglements results, as several hundreds of pounds of high explosives may be so carried and exploded and, obviously, the device is also destroyed, having fulfilled its intent.

As hereinbefore stated, we do limit ourselves to specific structural details, our only limitation being that of an automatic carrier for an explosive charge, started, controlled, and fired from a point at a distance from the target, on land. 65

Having fully described our invention, 70 what we claim as new, and desire to secure by Letters Patent, is:—

A device of the class described, comprising a frame, front and rear axles rotatable therein, spiked wheels fixed to the respective 75 axles, sprocket wheels on said axles, chains connecting the respective sprocket wheels, a motor for one of said axles, a shield for said motor, a container for explosives on said frame, and means at a distance from said device for firing said explosives. 80

In testimony whereof we have signed our names to this specification in the presence of two subscribing witnesses.

VICTOR A. VILLAR.
STAFFORD C. TALBOT.
